UNITED STATES PATENT OFFICE.

WALTER WRIGHT, OF NEW YORK, N. Y., ASSIGNOR TO ADDRESSOGRAPH COMPANY, OF CHICAGO, ILLINOIS, A CORPORATION OF ILLINOIS.

PRINTING MECHANISM.

1,183,333.

Specification of Letters Patent.

Patented May 16, 1916.

Substitute for application Serial No. 289,765, filed December 1, 1905. Renewed March 23, 1909, Serial No. 485,232. This application filed August 11, 1915. Serial No. 45,041.

To all whom it may concern:

Be it known that I, WALTER WRIGHT, a citizen of the United States, residing at New York city, in the county and State of New York, have invented certain new and useful Improvements in Printing Mechanism, of which the following is a specification.

This invention relates to improvements in printing mechanism, and especially to that class of mechanism used for printing manifold copies resembling typewritten matter, the object of the invention being to provide an apparatus of this character which will print such copies with great rapidity. With this main object in view, the principal improvements are to provide means for feeding the sheets of paper on to the bed in both directions of reciprocation thereof.

In the accompanying drawing Figure 1 is a longitudinal section of the apparatus, certain parts being shown in side elevation; Fig. 2 is a side view of the apparatus; Fig. 3 is a broken plan view of the lower portion of the apparatus; Fig. 4 is a detail sectional view of the side of a paper box; Fig. 5 is a broken plan view of the end of a guide roller; Fig. 6 is a plan view of the whole apparatus; Fig. 7 is a plan view of the feed box being removed; Fig. 8 is a broken end elevation of the same; Fig. 9 is a sectional view of one of the boxes for the cylinder; Fig. 10 is a plan view of the end of one of the ribbon feed shafts; and Fig. 11 is a longitudinal section of the same.

Referring to the drawings, 1 represents a frame on which the apparatus is mounted, the bed 2 moving on ball bearings 3 in grooves 4 in the top of the frame. In said bed 2 is contained the chase 5 with the type surface 6. To reciprocate said bed there is provided a transverse shaft 7 rotated by the usual crank handle, not shown, which shaft 7 has secured thereon, adjacent to each side of the frame, a wheel 8 having two segment gears 9, 10, of which the segment gear 9 is substantially a semi-circular gear and of smaller radius while the segment gear 10 is slightly less than a semi-circular gear but of larger radius. The gear 10 meshes direct with a rack 11 secured underneath the corresponding side of the bed, while the gear 9 meshes with a pinion 12 mounted upon a transverse shaft 13, said pinion itself

engaging said rack. With this mechanism there is produced from the continuous rotary motion of the shaft a reciprocating motion of the bed, for, as the end of the segment gear 10 passes the vertical plane through the shaft 7 and travels out of mesh with the rack 11, the semi-circular gear 9 travels into mesh with the pinion 12 causing said pinion to revolve in the opposite direction to that in which it had been just revolving, and imparting a backward movement to the rack 11. When the rear end of the semi-circular gear 9 passes away from the pinion 12, the advancing end of the segment gear 10 comes into mesh with the rack 11 causing it and the pinion 12 to travel in the opposite direction. This contrivance enables the apparatus to be operated at great speed.

For the purpose of obtaining rapidity of printing with this class of devices, there is provided mechanism for feeding and printing sheets during each movement of reciprocation of the bed. For this purpose on each side of the center of the machine is a feed frame 14 extending obliquely upward and outward from a point near the center, in which frame is placed a box 15 having its ends 17 oblique to the back 18, said box containing the pile of sheets to be delivered from that side to the printing mechanism. The sides of the frame 14 have lips or flanges 19 bent inward over the edge of the box to hold the sheets in the box. Within the box is a false bottom 20 which has pins 21 extending through slots 22 in the sides of the box and is drawn forward to the front of the frame by springs 23. This construction insures that the uppermost sheet of the pile is always pressed against a roller 24 carried upon a shaft 25, the end of said shaft having a small gear 26 meshing with an internal segment rack 27, carried upon the end of a lever 28 pivoted on the feed frame 14 at 29 and having a downwardly extending finger 30. Said racks for the two feed frames are on opposite sides of the machine, and the corresponding downwardly extending finger 30 is adapted to be engaged by a post 31 on the same side of the machine. Supposing that the bed in Fig. 1 is moving from left to right, said post 31 impinges upon the finger 30 and causes the lever 28 to oscillate, and thereby to impart a

left-handed rotary motion to the feed roller 24 on the right causing the underside of said feed roller, which is in contact with the uppermost sheet of paper, to move upward, 5 and drawing the lower edge of said sheet above the upper edge of a rim or lip 33 bent upward from the bottom of the frame 14. As the finger is thus rocked by the movement of the post, it is caused to contact with a downwardly extending spring 34, and then to compress said spring, so that, as soon as the post escapes from the finger, the spring throws the finger back slightly but sufficiently far to be engaged by 10 the post upon its return movement. Now when the post returns it impinges against the other side of the finger, causing the lever 28 to rock in the opposite direction, and imparting a right handed rotary motion to the 20 roller, causing the sheet of paper, which is always pressed against said roller 24 by the springs 23, to descend and pass over the lip 33 and then between the cylinder 37 and a guide roller 38. The sheet of paper then 25 passes over the ribbon 39 and between said ribbon and the cylinder 37, and into the bite of the cylinder and bed, and, in the movement of the bed, is carried therewith, the cylinder being free (not geared to the 30 bed) and rotated by the pressure imparted through the paper. Such cylinder 37, or roller, is of small diameter so that its circumference is less in length than the distance traveled by the reciprocating bed. It 35 therefore makes more than a single revolution in making the impression and at the same time provides for close juxtaposition of the paper feeding means to the line of impression. Said ribbon 39 is wound upon 40 two rollers 40 carried upon the ends of the bed and is wound up upon one of said rollers and wound off from the other by the following mechanism. Upon the shaft 41 of the winding roller is slidably mounted, 45 but keyed theron, as shown at 42 a crown ratchet wheel 43, which is adapted to engage a similar wheel 44 extending from the side of a gear wheel 45. Said gear wheel 45 engages a short rack 46 at the end of the 50 frame, and thereby, at the end of any movement of the bed the gear wheel 45 is turned, and the crown ratchet wheel 44 secured to said gear wheel, operatively engaging the crown ratchet wheel 43 on the shaft 55 41, imparts rotation to said shaft, but, upon the return movement, when the gear wheel 45 is turned in the opposite direction, said ratchet teeth escape each other, since the 60 movable ratchet wheel 43 is pressed against the ratchet wheel 44 by a very light coiled spring 47, easily compressed, so that the ratchet teeth can easily slip past each other. By this means a slight winding movement is given to the ribbon at each complete 65 reciprocation. After the ribbon has been fully

wound up on one roller, the rack is depressed at that end and the other rack raised into an operative position, by means of a slot 48 and screw 49, and the ribbon is then wound upon the other roller. 70

The sheet which has been printed through the inking ribbon is carried on with the bed by the pressure between the bed and the revolving cylinder until it arrives at guides 50, which extend downward toward 75 the center of the machine, one at each side of the ribbon and class, and under the edges of the paper, which itself extends beyond the sides of the ribbon. Said guides thereby raise the paper and guide it between two rollers 80 51, 52, having bearings in brackets 53 depending from the feed frame. The function of these rollers is to continue the discharge movement of the printed paper. For, although the pressure between the cylinder 85 and bed will feed the printed paper forward between said rollers 51, 52, a part of its length, yet, when the rear end of the sheet of paper arrives at the bottom of the cylinder 37, said paper will no longer be 90 fed forward thereby between said rollers, and the return movement of the bed would carry the paper back again, were not means provided for avoiding said backward movement. It is for this purpose that the rollers 95 51, 52, are provided, for the lower roller shaft carries a gear wheel 54 loosely mounted thereon in precisely the same manner as the gear wheel 45 was mounted upon the winding shaft 41, and having a similar connection with said shaft by means of crown ratchet wheels 55, 56, so that in the forward movement of the bed and rack the motion of the gear wheel does not impart any rearward movement to the roller 51, on account 100 of the ratchet teeth slipping past each other, whereas immediately that the bed begins to return and motion is imparted to the gear wheel 54 of the roller 51, say, on the left hand side in a left handed direction the 110 shaft of the roller 51 is correspondingly revolved by reason of the ratchet teeth operatively engaging each other and thereby the forward movement of the sheet of paper is continued. The surface of the roller 51, is 115 preferably made of absorbent material, which prevents the ink laid upon the paper from being smeared in passing between said rollers. From said rollers 51, 52, the paper passes from between two guides 57, 58 which 120 serve to prevent the paper falling upon the inking roller. By these guides the sheet of paper is discharged on to the pile of printed sheets. 125

In order to insure an accurate feed of the sheets of paper between the cylinder and the feed rollers, while at the same time providing for the proper pressure upon the sheet in passing between the cylinder and the inking ribbon, the ends of the shaft of 130

the cylinder 37 have their bearings in blocks 59 slideable in vertical guides 60, pressed upward by springs 61 and adjustably depressed by screws 62. These screws serve to hold down the cylinder upon the inking ribbon. In recesses 63 in the sides of the blocks 59 are mounted the bearings 64 for the shafts of the guide rollers 38, said bearings being pressed outward by springs 65 and adjustably pressed inward by screws 66. The sides of the guides are slotted as shown at 67 to permit said screws to pass therethrough.

I claim:

- 15 1. In a printing apparatus, the combination, with the reciprocating bed, of a frame extending upward and outward at each side of the center of motion of the bed, means for supporting the pile of sheets in each frame, and means operated by the motion in opposite directions of the bed for feeding the uppermost sheet of each pile alternately to the bed, substantially as described.
- 20 2. In a printing apparatus, the combination, with the reciprocating bed, of a frame extending upward and outward at each side of the center of motion of the bed, a cylinder above the center of the bed, means for supporting the pile of sheets in each frame, and means operated by the motion in opposite directions of the bed for feeding the uppermost sheet of each pile between the cylinder and the bed, alternately to the bed, substantially as described.
- 25 3. In a printing apparatus, the combination, with the reciprocating bed, of a frame extending upward and outward at each side of the center of motion of the bed, and comprising a rim or lip for supporting a pile of sheets, and means for raising the uppermost sheet above said rim or lip in one movement of the bed and moving it down past said rim or lip in the opposite movement, substantially as described.
- 30 4. In a printing apparatus, the combination, with the reciprocating bed, of a frame extending upward and outward at each side of the center of motion of the bed, means for supporting the pile of sheets in each frame, a roller over each frame, springs for pressing the uppermost sheet against the rollers, and means for rocking each roller correspondingly with the reciprocating movement of the bed, substantially as de-
- 35 scribed.
- 45 5. In a printing apparatus, the combination, with the reciprocating bed, of a frame extending upward and outward at each side of the center of motion of the bed, means for supporting the pile of sheets in each frame, a roller over each frame, springs for pressing the uppermost sheet against the rollers, a rim or lip for retaining the lower edge of the uppermost sheet, the motion of the roller first raising said sheet

above said rim, and then moving it down over the same, and means for rocking each roller correspondingly with the reciprocating movement of the bed, substantially as described.

6. In a printing apparatus, the combination, with the reciprocating bed, of a frame extending upward and outward at each side of the center of motion of the bed, means for supporting the pile of sheets in each frame, a roller over each frame, springs for pressing the uppermost sheet against the rollers, and means for rocking each roller correspondingly with the reciprocating movement of the bed, said means comprising a post carried by the bed, and a rocking lever rocked by said post and operatively connected with the roller, substantially as described.

7. In a printing apparatus, the combination, with the reciprocating bed, of a cylinder thereover, means for feeding a sheet of paper between said bed and cylinder, rollers between which the sheet of paper is guided, and a direct connection between the bed and said rollers for rotating said rollers by the movement of the bed, operative in one direction of said movement, and inoperative in the other direction, substantially as described.

8. In a printing apparatus, the combination of a bed, a cylinder thereover, a feeding device at each side of the cylinder for feeding the sheets between said bed and cylinder, and rollers between which sheets of paper so fed alternately in opposite directions are guided, said rollers being revolved by said movement of the bed in one direction, but not revolved thereby in the opposite direction, substantially as described.

9. The combination with a reciprocating bed and an impression cylinder, of a frame on each side of the impression cylinder and extending obliquely upwardly and outwardly therefrom, a sheet-containing box for each frame, nibs or flanges 19 to hold the sheets in each box, a false bottom in each box, springs to draw the false bottoms forward, rollers against which the sheets are pressed by said springs, means connected to said bed to turn said rollers, and means co-operating with said rollers to feed the sheets to the bite of the cylinder and bed.

10. The combination with a reciprocating bed and an impression cylinder, of a frame on each side of the impression cylinder and extending obliquely upwardly and outwardly therefrom, a sheet-containing box for each frame, nibs or flanges 19 to hold the sheets in each box, a false bottom in each box, springs to draw the false bottoms forward, rollers against which the sheets are pressed by said springs, pinions on said rollers, gears meshing with said pinions and car-

- ried upon the ends of levers, and means on the bed for reciprocating said levers.
11. The combination with a reciprocating bed and an impression cylinder, of a frame 5 on each side of the impression cylinder and extending obliquely upwardly and outwardly therefrom, a sheet-containing box for each frame, nibs or flanges 19 to hold the sheets in each box, a false bottom in each box, springs to draw the false bottoms forward, rollers against which the sheets are pressed by said springs, means connected to said bed to turn said rollers, means cooperating with said rollers to feed the sheets 10 to the bite of the cylinder and bed, and arms or lips 33 bent upward from the bottom of each frame.
12. The combination with a reciprocating bed and an impression cylinder, of a frame 20 on each side of the impression cylinder, and extending obliquely upwardly and outwardly therefrom, a sheet-containing box for each frame, nibs or flanges 19 to hold the sheets in each box, a false bottom in each 25 box, springs to draw the false bottoms forward, rollers against which the sheets are pressed by said springs, pinions on said rollers, gears meshing with said pinions and carried upon the ends of levers, means on the bed for reciprocating said levers and springs 34 to start said levers in motion.
13. The combination with a reciprocating bed and an impression cylinder, of a frame 30 on each side of the impression cylinder and extending obliquely upwardly and outwardly therefrom, a sheet-containing box for each frame, nibs or flanges 19 to hold the sheets in each box, a lip extending upward on each frame at the bottom, a false 35 bottom in each box, springs to draw the false bottom forward, rollers against which the sheets are pressed by said springs, means connected to said bed to turn said rollers, and means cooperating with said rollers to 40 feed the sheets to the bite of the cylinder and bed, the construction and arrangement being such that the roller turns in one direction to draw the sheet from said lip, and then turns in the other direction to feed the 45 sheet downwardly toward the bed.
14. The combination with a bed and an impression cylinder of which one is mounted to reciprocate relatively to the other, the said bed having a ribbon thereon and substantially parallel therewith, of paper feed 55 device for delivering paper directly to the angle or bite of the cylinder and bed and above the ribbon, and a roller located at said angle and receiving the paper from the 60 feed device, said roller co-acting with the impression cylinder to direct the same onto the ribbon and beneath the impression cylinder.
15. The combination with a bed and an impression cylinder, of which one is mounted 65
- ed to reciprocate relatively to the other, of means at one side of the cylinder for supporting sheets of paper to be printed, means for directing a sheet from said supporting means to the bed at the angle formed by the cylinder and bed, and a roller at said angle in close relation with said cylinder and co-acting therewith to deliver the paper at a point beneath the cylinder.
16. The combination with an impression cylinder, and a reciprocating bed, of a support for sheets, inclined to the bed, and feed devices for delivering sheets from said inclined support at an angle to the bed and into the angle formed by the bed and cylinder including a roller co-acting with said cylinder, the said sheet support being spaced above the bed to permit passage of a sheet beneath the support after the sheet leaves the cylinder.
17. In a machine for printing imitation typewritten matter, the combination of a type-surfaced ribbon-covered bed, an impression roller coacting therewith, a paper magazine mounted in permanent relation to the impression roller, with its delivery end directed toward the line of engagement of said roller upon the ribbon-covered bed, automatic means for successively directing paper sheets from the magazine into frictional surface engagement with the impression roller, and means for discharging the printed sheet.
18. In a machine for printing imitation typewritten matter, the combination of a type-surfaced ribbon-covered bed, an impression roller coacting therewith, an auxiliary roller engaging the impression roller in the space between the same and the ribbon on the bed, a paper magazine mounted in permanent relation to the impression roller, automatic means for directing the paper from the magazine into the space between the said auxiliary and impression rollers, and means for discharging the printed paper.
19. In a machine for printing imitation typewritten matter, a reciprocating type-surfaced ribbon-covered bed, an impression roller coacting therewith and having a circumference less than the travel of the bed, a paper magazine mounted with its delivery end adjacent to the line of printing engagement between the bed and impression roller, automatic means for directing the sheet from such magazine directly into frictional holding contact with the surface of said roller, and means for discharging the printed sheet.
20. In a machine for printing imitation typewritten matter, a reciprocating ribbon-covered bed, an impression roller coacting therewith and having a circumference less than the length of the bed, a paper magazine mounted with its delivery end adjacent to

- the line of printing engagement between the bed and the impression roller, a pressure roller engaging the topmost sheet in said paper magazine, means for oscillating said 5 roller to release and deliver said sheet into frictional contact with the surface of said impression roller, and means for discharging the printed sheet.
21. In a machine for printing imitation 10 typewritten matter, the combination of a ribbon-covered bed, an impression roller coacting therewith and having a circumference less than the length of said bed, a paper magazine having its delivery end pointed into 15 the angle between the roller and bed, automatic means, including a pressure roller, on the magazine for directing the paper into frictional contact with the surface of said impression roller, and means for lifting the 20 printed end of the sheet preparatory to its removal from the machine.
22. In a machine for printing imitation 25 typewritten matter, the combination with a type-surfaced ribbon-covered bed, of an impression roller coacting therewith, a frame extending upward at each side of the roller, means for supporting a pile of sheets in each frame, and means operated by the relative motion between the bed and roller for feeding 30 the uppermost sheet of each pile alternately to the bed.
23. A machine for printing imitation 35 typewritten matter, comprising two coacting relatively reciprocating members, one an impression roller and the other a type-surfaced bed, means for automatically feeding sheets 40 of paper into the angle between said roller and bed, and means for raising one end of the sheet preparatory to the discharge of the same from the machine.
24. The combination of a bed, an impression roller making more than a complete revolution on coöperation with the bed, means in fixed relation to the roller for supporting a plurality of sheets of paper and placing them, one after another, automatically on the bed, and operating means independent of the impression roller for removing the paper from the bed.
25. In a printing mechanism, the combination of a bed adapted to carry a page 45 form of type surface, means for holding an inking ribbon in contact with such form, an impression roller, means for moving the bed back and forth beneath the roller, and means 50 independent of the roller for automatically removing from the bed the paper laid thereon on each reciprocation thereof.
26. The combination of a bed, a platen, means for automatically feeding paper between the bed and platen, means for automatically raising one end of a sheet of paper which is thus placed on the bed, said raising being at the opposite end of the bed from 55 the platen and coming after that portion of the sheet has been printed by the bed and platen, and mechanism adapted to grasp such raised end and withdraw the sheet.

WALTER WRIGHT.
